UNITED STATES PATENT OFFICE.

ERNEST O. FREDERICS, OF NEW YORK, N. Y., ASSIGNOR TO E. FREDERICS, INC., OF NEW YORK, N. Y., A CORPORATION OF NEW YORK.

HAIR WAVING AND CURLING DEVICE.

Application filed August 8, 1924. Serial No. 730,855.

To all whom it may concern:

Be it known that I, ERNEST O. FREDERICS, a citizen of the United States of America, and a resident of New York, in the county 5 of New York, in the State of New York, have invented new and useful Improvements in Hair Waving and Curling Devices, of which the following, taken in connection with the accompanying drawings, is a full, 10 clear, and exact description.

This invention relates to a hair curler or device for producing permanent waves involving the use of a tapered tubular bearing and opposite end heads connected to each 15 other through the barrel for simultaneous rotation relatively thereto in one direction together with means for preventing such relative rotation in a reverse direction, one of the end heads serving as a means for engaging a limited quantity of hair to be wound around the barrel, while the other end head serves as a handle or operating member by which the first named end may 20 be turned to produce the desired stretching of the hair when wound upon the barrel as the first step in the curling or permanent 25 waving of the hair.

In devices of this character, the hair-engaging head is usually slotted to receive a 30 thread or string which is tied to the strands of the hair to be waved for temporarily securing the strands to the waving device preparatory to winding and stretching the same around the barrel, and one of the objects of 35 the present invention is to provide one side of this head with a peripheral recess preferably extending to opposite sides of the slot to form a seat or rest for the strands of hair and thereby to prevent slipping of 40 the strands from the head, of the curler particularly at the beginning of the winding of the hair upon the barrel which not only renders the operation of holding the strands in place during such winding more convenient 45 to the operator, but also assures a more uniform winding of the hair upon the barrel and thereby secures a more lasting wave closer to the scalp as an essential requirement for permanent waving.

Furthermore, the joints in devices of 50 this character are necessarily close fitting but must be sufficiently free to permit the heads to be turned freely and easily in one direction relatively to the barrel, and it therefore follows that the slightest accumulation of

foreign matter either from the hair or from other sources, would interfere materially with the free operation of the movable parts, and another object of the present invention is to provide means for removing 60 such accumulations from the turning joints so as to permit free operation of the relatively movable parts at all times.

Other objects and uses relating to specific parts of the device will be brought out in 65 the following description.

In the drawings:

Figure 1 is a side view of a hair curling and waving device embodying the preferred 70 features of my invention.

Figure 2 is an enlarged longitudinal sectional view, partly in elevation and partly broken away, of the device shown in Figure 1.

Figure 3 is a longitudinal sectional view 75 of the device partly broken away.

Figure 4 is a face view of the detached barrel showing end slots for cleaning purposes.

Figure 5 is a sectional view of the barrel 80 shown in Figure 4.

Figure 6 is a face view of another modified form of barrel in which holes are provided for cleaning purposes, and Figure 7 is a sectional view of the barrel shown in 85 Figure 6.

As illustrated, this device comprises a longitudinally tapered tubular barrel 1— and opposite end heads 2— and 3— rotatably mounted thereon and operatively 90 connected for simultaneous rotation by means of a connecting rod 4— passing centrally through the barrel, said rod having one end threaded and engaged in an internally threaded socketed extension 5— 95 of the head 2— and its other end rigidly secured to and within the hub 6— of the head 4— by means of a pin 7—.

The end member 3— and adjacent end 100 of the barrel 1— are provided with registering coaxial sockets 8— and 8'— preferably of the same diameter for receiving the opposite ends of a spiral or helical spring 9— having its convolutions in close proximity to each other and its opposite ends engaging the corresponding end walls of the adjacent sockets, said spring being tensioned to frictionally engage the peripheral walls of the sockets 8— and 8'— and is wound in such manner that 110

the end members and their connecting rod —4— may be turned freely in one direction but are prevented from turning in an opposite direction by reason of the tendency of 5 the spring to expand and thereby to increase the friction to such an extent as to resist reverse turning movement.

That is, the coiled spring —9— is compressed between the end walls of the sockets —8— and —8'— so that its convolutions lie in close relation or in contact with one another thereby maintaining a uniform exterior diameter of the coiled spring for frictional engagement with the inner walls 10 of said sockets, the ends of the spring being unattached and tensioned so as to spring against the adjacent portions of the inner annular walls of the sockets which permits 15 free rotation of the head —3— in the direction of winding of the coil but prevents reverse rotation of said head by reason of the frictional engagement of the ends of the coil with the annular walls of the sockets —8— and —8'— tending to expand the coil 20 and the inability of the coil to expand owing to its close engagement with the annular walls of the sockets.

The tubular extension —5— of the end member —2— is tightly screwed upon the 25 adjacent threaded end of the connecting rod —4— to rotate therewith when operated by the turning of the end member —3— which constitutes the handle or operating member for said rod and end member —2— and 30 for that purpose is provided with a knurled periphery.

The portion of the end member —3— 35 inclosing the adjacent end of the spring —9— is preferably of greater diameter than the adjacent end of the barrel —1— and is provided with a socketed inner end journaled upon the periphery of the adjacent end of the barrel —1— for relative rotation theron, the parts being assembled in such 40 manner as to cause the adjacent end face of the barrel to abut snugly against the inner wall of the socket —10— as a means for limiting the relative axial movement of said barrel and end member —3— in one 45 direction when adjusted for use.

The tubular extension —5— of the end member —2— is telescopically journaled within the adjacent end of the barrel —1— and is preferably reduced to form an annular endthrust bearing adapted to engage the end face of the barrel to limit the relative movement of said member and barrel in one direction.

The connecting rod —4— serves not only 50 as a means for transmitting rotary motion from one end member to the other, but also serves to hold said end members in close contact with the adjacent ends of the barrel so as to form smooth and practically imperceptible joints therewith.

The outer end of the end member —2— is generally cylindrical and of substantially the same diameter as the adjacent smaller end of the barrel —1— except that it is provided with a lengthwise diametrical slot 70 —11— extending axially from its outer end face through the greater exposed portion of the head for receiving a string or other tie piece by which the strand of hair to be curled or waved is firmly held during the 75 waving process, the outer ends of the opposite ends of the opposite arms of the bifurcated end —2— being beveled at —12— to facilitate the entrance of the head into the hair and also the entrance of the ties into 80 the slot preparatory to winding the strand of hair around the head and barrel.

A further deviation from the cylindrical form is that one side only of the head is provided with a longitudinally concaved peripheral recess —13— as shown more clearly in Figures 1, 2 and 3 to form a seat or rest which is flat in cross section for the strand of hair and finger of the operator, particularly at the beginning of the winding operation.

That is, this longitudinally concaved recess enables the strand of hair to be more accurately laid therein and serves to confine the hairs of the strand more neatly, accurately and smoothly, preparatory to winding than would be possible without the use of a recess so that the process of winding and stretching may be carried out with greater certainty to assure the desired permanency 100 of the wave or curl.

During this process of waving, more or less foreign matter such as oil, borax and dust, forming more or less of a gum is liable to accumulate in the joints to such an extent as to interfere with the free operation of the movable parts and I have provided several methods of preventing this accumulation and permitting the operation of the moving parts with greater freedom for a 110 longer period of use than would be possible without such provision.

One of these methods consists in providing the periphery of the tubular extension —5— and also the periphery of the 115 larger end of the barrel —1— with spiral threads —14— and —14'—, the threads —14— being surrounded by the adjacent end of the barrel while the threads —14'— are surrounded by the adjacent end of the end member —3— so that any gum or foreign matter tending to accumulate in the joint as —a— is fed inwardly by repeated relative rotations of the end members —2— and —3— and barrel —1—, the threads —14— being adapted to feed the foreign matter into the barrel, while the threads —14'— operate to feed any foreign matter accumulating at the joint —a'— from within to the exterior of the barrel. 130

Another method of permitting the removal of foreign matter is to provide both ends of the barrel with lengthwise radial slots —16— as shown in Figures 4 and 5 or 5 the ends and intermediate portions of the barrel may be provided with radial openings as shown in Figures 6 and 7 for the same purpose, it being understood that under these constructions, any loose foreign 10 matter which may tend to accumulate in the barrel will work out through the openings —16— and —16'—, assisted by the threads —14— and —14'—, and thereby reduces the liability of accumulations at the joints.

15

Operation.

If the hair has been properly tied in the usual manner and the tie slipped in the groove —11— of the end member —2—, the 20 strand of hair is laid in the concave groove —13— which automatically arranges the hairs of the strand in smooth straight relation and permits this relation to be maintained more uniformly throughout the 25 winding of the strand around the barrel preparatory to stretching and establishing the permanency of the wave.

After the hair is properly wound around the barrel, the end members are turned by 30 hand in one direction to tighten and stretch the hair on the barrel ready for further treatment if necessary, to make the wave more permanent.

During these repeated operations of the

end members —2— and —3— relatively 35 to the barrel, any foreign matter which tends to accumulate at the turning joints is removed by the threads —14— or —14'— or through the opening —16— or —16'— according to the method employed.

40 I claim:

1. In a hair waving and curling device of the character described, a tubular section having one end threaded externally, an end section journaled on said threaded 45 end, an additional end section having an externally threaded extension journaled in the other end of the tubular section, and means extending through the tubular section for transmitting rotary motion from one end 50 section to the other end section.

2. In a device for curling and waving hair, a tubular barrel having relatively rotatable end members journaled thereon, one 55 of the end members being provided with peripheral threads for removing accumulations of foreign matter from the turning joints.

3. A device for curling and waving hair comprising a tubular barrel having relatively rotatable end members journaled thereon, one of the parts being provided 60 with helical threads for removing accumulations of foreign matter from the turning joint.

65 In witness whereof I have hereunto set my hand this 31st day of July, 1924.

ERNEST O. FREDERICS.
